UNITED STATES PATENT OFFICE.

EUGÈNE SCHNEIDER, OF LE CREUZOT, FRANCE.

SECTIONAL GUN.

1,198,668.

Specification of Letters Patent. Patented Sept. 19, 1916.

Application filed March 2, 1916. Serial No. 81,782.

To all whom it may concern:

Be it known that I, EUGÈNE SCHNEIDER, a citizen of the Republic of France, residing at Le Creuzot, France, have invented a new 5 and useful Improvement in Sectional Guns, which is fully set forth in the following specification.

This invention has for its object to provide an improved light sectional gun capable of being readily taken to pieces and transported, so that it can be quickly set up near a trench and be taken to pieces for 10 transport by hand by troops in an attack.

The invention will now be more particularly described with reference to the accompanying drawings in which:—

Figures 1, 2 and 3 are respectively a side elevation, a rear end elevation, and a plan of one constructional example of the improved 20 gun. Fig. 4 is a side elevation partly in section on a larger scale, illustrating details. Figs. 5 and 6 are horizontal sections on the lines V—V and VI—VI respectively of Fig. 4. Fig. 7 is a partial side elevation viewed 25 from the right hand of Fig. 6, illustrating details of the lower portion of the pivot-supporting base. Figs. 8, 9 and 10 are views drawn to a larger scale illustrating the means for assembling the elements (pivot 30 and trunnion caps) forming the upper gun mounting. Fig. 8 is a side elevation partly in section on the line VIII—VIII of Fig. 10, and Figs. 9 and 10 are sections on the lines IX—IX and X—X respectively of 35 Fig. 8. Figs. 11 and 12 are respectively a side elevation and a cross section through the axis of the trunnions of the gun, illustrating the details of the means for attaching the removable shoulder piece. Figs. 13 and 14 40 are respectively a side elevation and a plan of a modified construction of the lower mounting.

The lower mounting of the improved sectional gun comprises a base A which supports the pivot and which is adapted to be assembled by interengagement in a base plate B which is fixed to a rear platform C that serves for carrying the anchoring spades.

50 The lower mounting is more particularly characterized by the feature that the base A is provided with a series of removable frames D, preferably a forward frame and two side frames, which serve in their operative position as supports for sandbags E (as shown in Figs. 1 to 5), or as abutments for

the insertion of suitable anchoring devices such as pegs F (as shown in Figs. 13 and 14).

In the example shown in Figs. 1 to 7, the interengagement between the base A and the base plate B is effected by means of a bayonet joint as shown in Figs. 4 to 7. For this purpose, the base plate B is formed with a series of nibs b designed to engage in notches a in the base A in assembling together the parts A and B. The assembling is effected by turning the base A through 45 degrees relatively to the base plate B, whereby a ramp a¹ on the edge of the base 70 A is caused to jam against the underside of the corresponding nib b (Figs. 4 and 5) and abut against the end b¹ of this nib.

The sandbag supports D are provided on their assembling edge with a transverse hinge pin d so formed as to enter and become engaged in the hinge straps A¹ on the base A.

For transport, the lower mounting is thus capable of being very quickly disassembled 80 into a number of its component parts, namely, the base plate B with its spade platform C; the pivot-carrying base A; and the several sandbag supports D.

The gun barrel G is journaled for instance 85 by means of hollow trunnions g formed on a trunnion hoop G¹ (Fig. 12) in a small mounting which can be disassembled into its usual component parts, namely a pivot H that is fixed to the base A by means of pins 90 h, and two trunnion caps I.

The pivot H and the trunnion caps I can be rapidly assembled together according to this invention, by the following means:— The trunnion caps I (Fig. 8) which are 95 hinged to the pivot H in the usual manner, by means of pins i, carry each at its free end, a hook I¹ engaging in a socket H¹ in the pivot so as to form an eye for the reception of the plug of a bolt of peculiar construction 100 working in a suitable recess in the pivot H. As shown in Figs. 9 and 10, this bolt comprises a plug J slideable in a recess h¹ in the pivot and fixed by means of a cross piece j to a spring stud K which is slideable in a 105 recess k² and is acted upon by a spring k. Normally, the stud is in the position shown in Figs. 9 and 10, the plug J having its full portion facing the socket H¹. To engage the hooks I¹ of the trunnion caps in the 110 sockets H¹, the studs have to be pushed inward, compressing the springs k, so as to

bring the notches J^1 of the plugs J facing the said sockets. Then the noses of the hooks I^1 can pass through the notches J^1 and enter the sockets H^1 as indicated in Fig. 8. 5 The trunnion caps are then locked in position by the circumstance that the springs k return the studs into the position shown in Figs. 9 and 10.

As shown more particularly in Fig. 4, the 10 trunnion caps I are provided with hooks I^2 for engagement with the holding devices L of a shield M which has its bottom edge engaged by a retaining ledge H^2 formed on the pivot H .

5 The gun comprises further a removable shoulder piece shown in detail in Figs. 11 and 12. The arm N of the shoulder piece is formed for this purpose with a tenon n having two nibs n^1 . By moving the arm N into position at right angles to the axis of the gun barrel in front of two notches in one of the hollow trunnions g , the nibs n^1 are able to enter these notches, and by moving the arm N into position parallel to the said axis 5 the nibs n^1 will come behind two retaining shoulders g^1 . The attachment of the shoulder piece to the gun is then completed automatically by means of an engaging device, for instance such as that shown in Fig. 11, 0 consisting of a spring bolt O which is mounted in the arm N and engages with its nose in a socket P in the gun barrel.

In the modification shown in Figs. 13 and 14, the lower mounting comprises in addition to the base A , only a base plate B to which are fixed a forward and a rear platform Q provided with a suitable number of sockets for small anchoring spades F .

What I claim is:—

1. In a light sectional gun, more particularly for trench use, the combination with the vertical pivot of the gun, of a lower gun mounting comprising a base for receiving said pivot, a base plate, means for detachably connecting said base to said base plate, a spade platform fixed to said base plate, and frames detachably connected to said base plate, serving in their approximately horizontal position as supports for sandbags, and as holders for spades or the like.

2. In a light sectional gun, more particularly for trench use, the combination with

the vertical gun pivot, and each trunnion cap of the gun, and a hinge pin for hinging each said cap to said pivot, of a notched spring bolt for detachably fastening the free end of each said cap to said pivot. 55

3. In a light sectional gun, more particularly for trench use, the combination with the vertical pivot and the trunnion caps of the gun, of a shield, a hook on each of said trunnion caps, holding devices on said shield adapted to be engaged by the hooks on said trunnion caps, and a retaining ledge on the 60 gun pivot, adapted to be engaged by the lower edge of the shield. 65

4. In a light sectional gun, more particularly for trench use, the combination of a removable shoulder piece, a bayonet joint 70 for attaching said shoulder piece to one of the trunnions of the gun, and an automatic engaging device comprising a spring bolt between the arm of said shoulder piece and the gun barrel. 75

5. In a light sectional gun, the combination with the vertical pivot of the gun, of a lower gun mounting comprising a base for receiving said pivot, a base-plate, means for detachably connecting said base to said base-plate, and anchoring frames detachably connected to said base-plate. 80

6. In a light sectional gun, the combination with the vertical gun pivot, of movably mounted trunnion caps for the gun each 85 provided with a hook-like free end, said pivot being provided with recesses to receive the free ends of said caps, and notched locking bolts for retaining said free ends within said recesses. 90

7. In a light sectional gun, the combination with the vertical pivot and the trunnion caps of the gun, of a shield, coating means on said shield and caps for detachably securing said shield in position, and a 95 retaining ledge on said pivot for engaging the lower edge of said shield.

Dated this 31st day of January 1916.

In testimony whereof I have signed this specification in the presence of two subscribing witnesses. 100

EUGÈNE SCHNEIDER.
